182,440

BUILDING

Roy Roth, Westport, Conn., assignor to Connecticut Automatics, Incorporated, New Haven, Conn., a corporation of Connecticut

Application May 10, 1956, Serial No. 41,427

Term of patent 14 years

(Cl. D13—1)

Fig. 1 is a perspective view of a building showing my new design;

Fig. 2 is a side elevational view of one side;

Fig. 3 is a side elevational view of the other side;

Fig. 4 is a top plan view; and

Fig. 5 is a front elevational view.

I claim:

The ornamental design for a building, substantially as shown.
